U.S. PATENT DOCUMENTS

D. 339,191 9/1993 Vieyra **D23/377**

FIG. 1 is a perspective view of the combined neon ceiling fan motor housing and support rod showing our new design;

FIG. 2 is a bottom view thereof;

FIG. 3 is a top view thereof; and,

FIG. 4 is a front side view thereof, the other sides views thereof being the same.

The support rod has been shown broken away at the bottom in FIGS. 1 and 4 to indicate indeterminate length.
